UNITED STATES PATENT OFFICE.

CHARLES P. BREESE, OF NORFOLK, VIRGINIA, ASSIGNOR TO HALL SIGNAL COMPANY, A CORPORATION OF MAINE.

ELECTRIC CONTROLLING SYSTEM.

No. 862,441.

Specification of Letters Patent.

Patented Aug. 6, 1907.

Application filed August 11, 1902. Serial No. 119,185.

To all whom it may concern:

Be it known that I, CHARLES P. BREESE, a citizen of the United States, and a resident of Norfolk, county of Norfolk, and State of Virginia, have invented certain new and useful Improvements in Electric Controlling Systems, of which the following is a specification.

This invention relates to means for controlling a plurality of motors or other electrical devices located 10 at a distance from the source of supply.

It particularly relates to means for electrically controlling a conveyance, such as a car, and its object is to provide an arrangement of instrumentalities which will automatically operate to prevent collisions between the said conveyances.

The invention consists first in providing a means for controlling the quantity of current fed to the car or conveyance by an instrument or instruments located in proximity to the car. The invention consists, 20 in addition thereto, in providing a means for controlling the quantity of current fed to the contact wire, according to the position of the car along the wire.

The invention also consists in providing bodies of different resistances for controlling the amount of current fed to the said contact wire, and providing means controlled by the current flowing to the contact wire, at one point for changing the circuit connections of the resistance body at another point.

The invention further consists in providing a means 30 which will prevent any change in the uniformity of the current fed to the said contact wire at one point until after the circuit at that point between the said contact wire and the return conductor has been broken.

The invention also consists in other features of construction and combinations of parts hereinafter described and claimed.

The invention is illustrated in the accompanying drawings, in which

Figure 1 illustrates my invention as applied to a 40 railway street car system; and Fig. 2 illustrates a detail forming part of the said system. Fig. 3 is a detail view of some of the parts shown in Fig. 1 with connections.

In Fig. 1, 1 indicates a dynamo for supplying the 45 current to the said system. 2 indicates the main feed conductor or wire for supplying the system at different points along the track of the car. 3 indicates a contact wire which feeds the current to the car. The connection between the contact wire 3 and the car 4 is 50 made by means of the trolley 5 in the manner well known in the art. The circuit on the trolley 5 is completed through the switch or rheostat and the motor of

the car to the return conductor or rails 36, which is, in turn, connected to the dynamo 1. The contact wire is divided into a plurality of contact sections. The 55 said sections are insulated from each other and receive the current from the main feed wire. The amount of current which is fed to the sections is controlled by instruments associated with each of the said sections.

The contact sections of the contact wire are indicated by the numerals 6, 7 and 8. Three magnets are associated with each of the said sections for controlling the amount of current fed to an adjoining section. These magnets are indicated by numerals 9, 10 and 11 and are normally connected directly in circuit between 60 the main feed wire 2 and the contact sections 6, 7, 8 of the contact wire 3. The circuits through these electro-magnets are normally completed through the car 4 as it passes along the track. The current coming from the dynamo 1 passes to the main feed wire or 70 conductor 2 through the connecting wires 12, 13 or 14 to the electro-magnets 9, 10 or 11, the contact sections 6, 7 or 8, according to the position of the car relative to the said contact wire. From the car, the current passes by way of the return conductor or the rail 36 75 back to the dynamo 1. The electro-magnets 10 and 11 control the electro-magnets 15, 16, which are connected directly to the return conductor 36. The magnets 15, 16 are also connected to the main feed wire 2 by the operation of the electro-magnets 10 and 80 11; that is, the low resistance magnets of a section adjoining to that of the high resistance magnets 15, 16 and 17. High resistance electro-magnets 18, 19 and 85 20 are also associated with the sections of the contact wire. These electro-magnets are connected to the main feed wire, and may be connected to the contact sections by the operation of the magnets 15, 16 and 17. The magnets 15, 16 and 17 also control the circuits of the low resistance magnets 9, 10 and 11, the armature of the said magnets 15, 16 and 17 being located between 90 contact points connected respectively with the magnets 9, 18, 10, 19, 11, 20, so that when the said magnets 15, 16 and 17 are energized, the circuits between the main feed wire 2 and the contact sections 6, 7 and 8 are established through magnets 18, 19 and 20 respectively. This controls the amount of current which is fed from the said main feed wire to each of the contact sections, so that when there is a connection made with magnets 9, 10, 11, a greater quantity of current is fed to the said contact section than when the connection is made through magnets 18, 19 and 20.

When a current is fed through the magnets 9, 10 and 11, its quantity is sufficient to operate the motor or other device of the electric car, but when the connec-

tion is made through the magnets 18, 19 and 20, the amount of current fed to each of the contact sections is insufficient to operate the motor or other device of the car, although it may be sufficient to allow the lamps of the car to slightly glow. The amount of current thus fed to the contact sections may be controlled by the magnets 15, 16 and 17 of the same sections. Magnets 15, 16 and 17 are controlled by the magnets of the adjoining sections. If now, the magnets 15, 16 and 17 are controlled by the presence of a car in an adjoining section, the motor or other device of the car located in that section may be controlled by the quantity of current fed to that section through the different resistance bodies of that section. If, however, a car should enter 10 one of the said sections, and the electro-magnet controlling the resistance circuits of that section should be energized by the presence of a car in the succeeding section, the low resistance circuit will be broken, and the magnet corresponding to the magnets 9, 10 and 11 will be deenergized and cannot be operated by the presence of the car in that section; therefore, in order to control the magnets used for controlling the resistance circuits of a preceding section, a further means is provided in the section to which the car is connected. 15 This means consists in providing a circuit connection controlled by the high resistance electro-magnets 18, 19 and 20, which will become energized by the presence of the car in their respective sections when the armature of the electro-magnets 15, 16 and 17 disconnect the electro-magnets 9, 10 and 11 from their respective contact sections, and connects electro-magnets 18, 19 and 20 in series with the contact sections.

When the magnets 18, 19 and 20 become energized, they draw up the armatures 24, 25 and 26, thereby closing circuits 27, 28 and 29 respectively, which lead to the magnets corresponding to the magnets 15, 16 and 17. These magnets also become energized and break the normal connections of the low resistance bodies, and connect the said preceding contact sections 40 with the high resistance body of that section, thereby reducing the amount of current that may be fed to that section. I have thus provided a means which will control the motors or other devices of the cars, whatever position the cars may be in relative to the said contact 45 section.

If two cars are located in adjoining sections, the circuit of one of the said sections will be through the high resistance body. If then, the other car enters a succeeding section, the circuit of the first-named car may 50 be reestablished through the low resistance body by the deenergization of the magnet corresponding to the magnets 15, 16 and 17 of that section. I prefer, however, to provide a means to prevent the reestablishment of the circuit through the low resistance bodies until after the circuit through the contact sections associated with the said resistance bodies is broken by the operator of the car. This will further avoid collision of the cars, and compel the motorman to break the circuit through the motor or other device 60 of the car before he can again start the car. This will allow for a resetting of the instruments and prevent burning out of the contacts of the instruments.

In Fig. 2 is illustrated diagrammatically the rheostat of a car motor. 30 indicates the cylinder containing the rheostat and controlling the mechanism of the

car. 31 indicates a handle for operating the said mechanism, and 32 illustrates a contact co-operating with a segmental contact 33 to break the circuit leading from the contact sections to the return conductor. The contact 32 is connected through the high resistance 40 to 70 the car wheel and from there to the return conductor 36. The rheostat is connected to the motor in the usual way, and thence to the return conductor 36. The resistance 40 will form a by-pass for the current which will be sufficient to cause the magnets 18, 19 75 and 20 to operate. The re-setting of the instruments will be accomplished only by breaking the circuit of this by-pass, as well as that of the motor. When this is done, the car may proceed.

The operation of the system is as follows. If a car 80 makes contact with section 7 on the contact wire, a circuit will be established from the dynamo 1 to the main feed wire 2 to the armature 25, the connecting wire 13, the low resistance electro-magnet 10, thence to the section 7, the car 4 located in that section, the 85 return conductor 36 back to the dynamo 1. The current passing through the electro-magnet 10 will cause its armature to make contact with its front contact. This will establish the circuit through the controlling magnet of the preceding section, namely, electro-magnet 15. The circuit through magnet 15 will be as follows. Dynamo 1, main feed wire 2, armature of magnet 10, connecting wire 21, electro-magnet 15, return conductor 36 back to dynamo 1. The current 90 passing through the electro-magnet 15 will cause its armature to break contact with its back contact and to make contact with its front contact, thereby changing the connections of the low resistance body and the high resistance body. The normal circuit is from the main feed wire through the electro-magnet 9, to the contact section 6, which will be changed to a circuit from the source of current, the main feed wire 2, the high resistance electro-magnet 18, the armature of the electro-magnet 15, to the contact section 6. If now, the car 4 makes connection with the contact section 8 by means 100 of the trolley 5, the flow of the current through the electro-magnet 10 will cease, the electro-magnet 10 will become deenergized and the circuit of the electro-magnet 15 will be broken and the said electro-magnet 15 will also become deenergized. This will 105 reestablish the circuits of the contact section 6, but the operation of the electro-magnet 11 of the contact section 8 will produce a similar result in the circuits of the contact 7 to that produced in the circuits of contact section 6, when the motor or other device of the car 110 was in circuit with contact section 7. If, however, a car makes contact with the contact section 6 while the car 4 is in circuit with the contact section 7, the electro-magnet 18 will be energized, since a circuit will be established from the main feed wire 2 to the 115 electro-magnet 18, the armature of the electro-magnet 15, the contact section 6, through the car in circuit with the contact section 6 back to the return conductor 36. Inasmuch as the amount of current fed to the said contact section is greatly decreased, the car will 120 be stopped and will not be able to move forward until after the circuit of the said contact section is broken, inasmuch as the electro-magnet 18 also establishes a circuit from the main feed wire to the armature 125 35, the contact section 6, through the car in contact with 130

the said contact section 6 back by way of the return conductor 36. This circuit will be established independent of the operation of the electro-magnet 15, and consequently, independent of the operation of any of the instruments of the adjoining sections. The quantity of current will, therefore, continue to be sufficiently low to prevent the operation of the motor or other device until the car in section 7 moves to section 8, and until the current which is flowing through the said high resistance electro-magnet 18 ceases, by breaking circuit through the motor or other device and the by-pass. When this is done, the circuit of contact section 6 will be re-established to the low resistance electro-magnet 9 and permit the operation of the motor or other device of the car which is in circuit with the contact section 6.

If car 4 is in contact with contact section 8, and a car is in contact with contact section 7, and there is no car in the section succeeding the contact section 8, the current of contact section 8 will be fed through the low resistance magnet 11, which will close a circuit through the high resistance electro-magnet 16 of contact section 7. This will connect contact section 7 with the main feed wire, 2 through the high resistance electro-magnet 19, and the amount of the current will diminish so as to prevent the operation of the motor or other device of the car in contact with the contact section 7. The magnet 19 will, moreover, be energized, while the magnet 10 will be deenergized by the operation of the electro-magnet 16. The magnet 19 will close a circuit from the main feed wire 2, armature 25 connecting wire 28, connecting wire 21, high resistance electro-magnet 15, return conductor 36. The electro-magnet 15 will disconnect the low resistance electro-magnet 9 from the contact section 6 and will connect the high resistance electro-magnet 18 with the contact section 6. This will then prevent the operation of the motor or other device of a car in contact with the contact section 6, until after the car in contact with contact section 7 makes contact with contact section 8, and until the circuit between the said contact section 6 and the conductor is broken, by removing the trolley from the trolley wire.

If there is a car in connection with the contact section 6, and a car in contact with contact section 7, the armature of the electro-magnet 15 will make contact with its front contact, and the circuit connection of contact section 6 will be through the high resistance electro-magnet 18. If there is no car in contact section 8, the car connected with contact section 7 may go either forward or backward. If the car backs so as to make connection with contact section 6, the circuit connections will be through the high resistance magnets 18 to contact section 6 and to the two cars connected to the said contact section 6, which will prevent the operation of the said cars until the circuit of both of the said cars is broken, thereby permitting the armature 35 of the electro-magnet 18 to break connection with its front contact, thus re-establishing the circuit.

By the above description, I have set forth one of the preferred forms of my invention, which may be used in directly controlling the motor of the car. This invention, however, may be used to control signals located directly within the car, and it may be varied and used for other purposes without, in any way, departing from the spirit of my invention.

What I claim as new and desire to secure by Letters Patent, is:—

1. In a car controlling system the combination of a main feed conductor, a contact conductor divided into insulated sections, each section normally connected with said feed conductor and means whereby two cars connected with the same section automatically control the movements of each other by varying the existing current. 70

2. In a car controlling system the combination of a main feed conductor, a contact conductor divided into insulated sections, each section normally connected with said feed conductor and means whereby the connection of two cars with one of said sections automatically controls the strength of current supplied to each car. 75

3. In a car controlling system the combination of a main feed conductor, a contact conductor divided into insulated sections, each section normally connected with said feed conductor, means for varying the resistance of said connection and means whereby two cars connected with the same section are mutually controllable. 80

4. In a car controlling system, the combination of a main feed conductor, an insulated contact section; a translating device inserted between the feed conductor and the insulated section through the circuit of which translating device motor current is supplied to the car, 90 and means controlled by the presence of a car in said section for controlling the supply of current through said translating device.

5. In a car controlling system, the combination of a main feed conductor, an insulated section, an electro-magnet inserted between the feed conductor and the insulated section, and means controlled by the presence of a car in said section for interrupting the flow of current through said magnet, substantially as described. 95

6. In an electric car controlling system, the combination of a main feed wire, a contact wire, a return conductor, a high resistance body and a low resistance body connected to the said main feed wire, means for connecting either the said high resistance body or the said low resistance body to the said contact wire. 100

7. In an electric car controlling system, the combination of a main feed conductor, a contact wire, a return conductor, a high resistance body and a low resistance body connected to the main feed conductor, an electro-magnet for connecting the said contact wire with either the said high resistance body or the said low resistance body and means associated with the said high resistance body for connecting the said high resistance body to the said contact wire. 105

8. In an electric car controlling system, the combination of a main feed wire, a contact wire, a return conductor, a high resistance body and a low resistance body, means for connecting the said contact wire with either the said high resistance body or the said low resistance body, and means associated with the said high resistance body for breaking the circuit of the said low resistance body. 110

9. In an electric car controlling system, the combination of a main feed wire, a contact wire, a return conductor, a high resistance body and a low resistance body connected to the said main feed wire, an electro-magnet and a means associated with the said high resistance body for disconnecting the circuit of the said low resistance body and establishing the circuit of the said high resistance body. 115

10. In an electric car controlling system, the combination of a main feed wire, a contact wire, a low resistance body, a plurality of high resistance bodies for controlling the amount of current fed from the said main feed wire to the said contact wire, means associated with one of the said high resistance bodies for disconnecting the circuit through the said low resistance body and establishing the 120 circuit through the other of the said high resistance bodies. 130

11. In an electric controlling system, the combination of a main feed wire, a low resistance magnet, a contact wire connected in the circuit of the said low resistance magnet and a plurality of high resistance magnets for controlling the circuit of the said contact wire and the said low resistance magnet. 140

12. In an electric controlling system, the combination of a main feed wire, a contact wire, a low resistance magnet and a high resistance body connected to the said main 145

- feed wire and the said contact wire, and means controlled by the said low resistance magnet for controlling the said high resistance body.
13. In an electric car controlling system, the combination of a contact conductor divided into sections, a main feed conductor, an electro-magnet connected with one of the sections of the said contact conductor and the adjacent portion of said feed conductor, means connectable with said section of said contact conductor for controlling the amount of current fed to the motor of the car, and a second magnet for controlling said means. 5
14. In an electric controlling system, the combination of a contact wire, an electro-magnet, a main feed wire connected to the said contact wire through the said electro-magnet, a high resistance electro-magnet connected to the armature of the first-named magnet and controlled thereby, and means associated with the said high resistance magnet for controlling the current passing through the motor of a car. 15
15. In an electric car controlling system, the combination of a contact wire, a main feed wire, a low resistance magnet connected to the said main feed wire and the said contact wire, a high resistance magnet associated with the low resistance magnet, a second high resistance magnet connected with the said main conductor and controlled by the first-named high resistance magnet. 20
16. In an electric car controlling system, the combination of a contact wire, a main feed wire, a low resistance magnet and a high resistance magnet connected with the main feed wire and the said contact wire, and means connected with the armature of the said low resistance magnet for controlling the circuit between the said high resistance magnet and the contact wire. 30
17. In an electric car controlling system, the combination of a main feed wire, a return wire, a contact wire, a magnet connected to the said main feed wire and to the said contact wire, an electro-magnet connected to the armature of the first-named magnet and to the said return conductor, and means associated with the second-named magnet for controlling the amount of current fed to the said contact wire. 35
18. In an electric car controlling system, the combination of a main feed wire, a contact wire, a return conductor, a high resistance magnet and a low resistance magnet connected in branch circuits between the said main feed wire and the said contact wire, an electro-magnet for establishing connections either through the high resistance magnet or the low resistance magnet, and means associated with the said high resistance magnet for preventing the said electro-magnet from reestablishing a circuit through the said low resistance magnet. 45
19. In an electric car controlling system, the combination of a main feed conductor, a contact wire, a return conductor, a high resistance body and a low resistance body connected in branch circuits between the said main feed conductor and the said contact wire, an electro-magnet for establishing connections between said contact wire and the said high resistance body or the said low resistance body. 55
20. In an electric car controlling system, the combination of a main feed wire, a contact wire, a return conductor, a high resistance body and a low resistance body connected in branch circuits between the said main feed wire and the said contact wire, an electro-magnet for establishing connections between the said contact and either the said low resistance body or the said high resistance body, and means associated with the said high resistance body for preventing the said electro-magnet from establishing connection between the said low resistance body and the said contact wire. 60
21. In an electric controlling system, a contact wire having a plurality of contact sections, a main feed wire, a low resistance magnet connected to the said main feed wire and to each of the said sections and means controlled by the said magnet for reducing the amount of current that is fed to an adjoining section of the said contact wire. 75
22. In an electric controlling system, the combination of a contact wire having a plurality of contact sections, electro-magnets, a main feed wire connected to the said contact sections through the said electro-magnets and means controlled by the armature of the said electro-magnet for reducing the amount of current fed to the adjoining section of the said contact wire. 80
23. In an electric car controlling system, the combination of a main feed wire and a main contact wire having a plurality of contact sections, an electromagnet connectable with the said main feed wire and with one of the contact sections, said sections being normally connected to said feed wire through said electromagnet, a high resistance magnet connected with the said main feed wire and connectable with one of the sections of the said contact wire and means associated with the first-named electromagnet for controlling the circuit of the said high resistance magnet. 95
24. In an electric car controlling system, the combination of a main feed wire, a contact wire having a plurality of contact sections, a return conductor, an electro-magnet, means associated with the said electro-magnet for limiting the amount of the current fed to each of the said sections until after the circuit is broken between each of the said contact sections and the said return conductor. 100
25. In an electric car controlling system, the combination of a main feed wire, a contact wire having a plurality of contact sections, a low resistance magnet connected to one of the said sections, a resistant body connected to the said main feed wire and another of the said sections, and means associated with the said low resistance magnet for controlling the circuit through the said resistance body. 105
26. In an electric car controlling system, the combination of a main feed wire, a contact wire having a plurality of contact sections, a low resistance magnet connected to the said feed wire and to the said contact wire, a high resistance magnet connected to the said main feed wire and to another of the said sections of the said contact wires, means controlled by the low resistance magnet for controlling the circuit of the said high resistance magnet. 110
27. In an electric car controlling system, the combination of a main feed wire, a contact wire having a plurality of contact sections, a return conductor, a low resistance body and a high resistance body connected to the main feed wire and each of the sections of the said contact wire, an electro-magnet connected to the said return conductor for controlling the circuit of the said resistance bodies. 115
28. In an electric car controlling system, the combination of a main feed wire, a contact wire having a plurality of contact sections, a return conductor, an electro-magnet, a resistance body controlled by the said electro-magnet and the said section, and means associated with the said resistance body which permits of a greater feed of the current to the said section only upon breaking the circuit between the said contact wire and the said return conductor. 120
29. In an electric car controlling system, the combination of a main feed wire, a contact wire having a plurality of contact sections, a low resistance body connected to the said main feed wire and to each of the said sections, a plurality of high resistance electro-magnets associated with each of the sections preceding the section of the said resistance body, one of the said high resistance electro-magnets controlled by the said low resistance body and the other of the said high resistance electro-magnets controlled by the first-named high resistance electro-magnet, whereby the amount of the current which is fed to each of the said sections is controlled. 125
30. In an electric car controlling system, the combination of a main feed wire, a contact wire having a plurality of contact sections, an electro-magnet connected to the said main feed wire and each of the said sections, a second magnet associated with an adjoining section for controlling the said first-mentioned electro-magnet of the said adjoining section, a high resistance body also controlled by the said second mentioned electro-magnet for controlling the amount of current fed to the said adjoining section. 130
31. In an electric car controlling system, the combination of a main feed conductor, a contact wire having a plurality of contact sections, an electro-magnet connected with the said main wire and each of the said sections, a high resistance electro-magnet controlled by the said electro-magnet and associated with each of the sections pre- 135

- ceding the sections of the said electro-magnet, the said high resistance electro-magnet in turn controlling the circuits of the said electro-magnets of the said preceding sections, a high resistance body having a circuit completed by the operation of the said high resistance electro-magnet and connected to the section preceding that of the first-named electro-magnet, whereby the amount of current fed to the said preceding section is controlled.
32. In an electric car controlling system, the combination of a main feed wire, a contact wire having a plurality of sections, a low resistance magnet and a high resistance magnet connected to the said main feed wire and associated with each of the said sections, a second high resistance electro-magnet controlled by the said low resistance magnet, which in turn controls the circuit of each of the said low resistance magnets and the first-named high resistance magnet of a section adjoining that of the first-named electro-magnet, whereby the current fed to the said sections is controlled.
33. In an electric car controlled system, the combination of a main feed conductor, a contact wire having a plurality of contact sections, an electro-magnet connected to the said main feed wire and connectible with each of the said sections, a second electro-magnet connected to the armature of the first-named electromagnet and connectible with a section adjoining the section of the first-named electro-magnet, and means connected to the second-named electro-magnet and the said adjoining section for controlling the amount of current fed to the said adjoining section.
34. In an electric car controlling system, the combination of a main feed wire, a contact wire having a plurality of contact sections, an electro-magnet connected with the said main feed wire and each of the said sections, a second magnet controlled by the first-named electro-magnet and associated with each of the said sections preceding that of the section associated with the first-named electro-magnet, a third electro-magnet associated with each of the said sections and controlled by the said second-named electro-magnet of each of the sections, the said third-named electro-magnet also controlling the current passing through the said second-named electro-magnet of each of the sections.
35. In an electric car controlling system, the combination of a main feed wire, a contact wire having a plurality of contact sections, a low resistance electro-magnet connected with the said main feed wire and each of the said sections, a plurality of high resistance magnets for controlling the current passing through the said low resistance electro-magnet, the said low resistance electro-magnet controlling the circuit passing through one of the said high resistance magnets associated with an adjoining section, the second high resistance electro-magnet also controlling the first-named high resistance electro-magnet of the said adjoining section, whereby the amount of current fed to the said adjoining section is controlled by the current passing to each of the sections.
36. In an electric car controlling system, the combination of a main feed wire, a contact wire having a plurality of contact sections, a plurality of high resistance electro-magnets associated with each of the said sections, a low resistance magnet also associated with each of the said sections for controlling the said high resistance electro-magnets of an adjoining section, one of the said high resistance electro-magnets controlling the circuit passing through the other of the said high resistance electro-magnets, the said second-named high resistance electro-magnet also controlling the circuit passing through the first-named high resistance electro-magnet of an adjoining section.
37. In an electric car controlling system, the combination of a main feed wire, a contact wire having a plurality of contact sections, a return conductor, a high resistance body and a low resistance body connected with the main feed wire and each of the said sections, means connected with the main feed wire and each of the said sections, means connected with the said high resistance body and the said low resistance body for controlling the amount of current fed to each of the preceding sections and means associated with the said high resistance body of each of the said preceding sections for establishing the current through

the said high resistance body until the said circuit is broken between the said contact section and the said return conductor.

38. In an electric car controlling system, the combination of a main feed wire, a contact wire having a plurality of contact sections, a return conductor, a high resistance body and a low resistance body connected to the said main feed wire and associated with each of the said contact sections, an electro-magnet associated with each of the said preceding sections and controlled by the said high resistance body and the said low resistance body, the said high resistance body and the said low resistance body of the said preceding section being controlled by the said electro-magnet, and means associated with the said high resistance body for establishing a circuit between the said main feed wire and its contact section through the said high resistance body.

39. In an electric car controlling system, the combination of a main feed wire, a contact wire having a plurality of contact sections, a return conductor, a high resistance body and a low resistance body connected to the said main feed wire and associated with each of the said contact sections, an electro-magnet associated with an adjoining section and connected to the said high resistance body and the said low resistance body and for connecting its associated contact section with the high resistance body and the low resistance body of that section, and means associated with the high resistance body of the last-mentioned section for preventing the said electro-magnet from establishing a circuit through the said low resistance magnet of that section.

40. In an electric car controlling system, the combination of a main feed wire, a contact wire having a plurality of contact sections, a return conductor, a low resistance magnet connected to the said main feed wire and each of the said contact sections, an electro-magnet associated with an adjoining section and controlled by the said low resistance magnet, a high resistance magnet connected to the said main feed wire and each of the said sections and also controlling the said electro-magnet associated with the said adjoining section, the circuit of the said high resistance electro-magnet and the said low resistance electro-magnet being controlled by the said first mentioned electro-magnet, whereby the amount of current fed to the section adjoining each of the said sections is controlled by the presence of the car in the said section.

41. In an electric car controlling system, the combination of a main feed wire, a contact wire having a plurality of contact sections, a return conductor, a low resistance magnet and a plurality of high resistance magnets associated with each of the said sections, the low resistance magnet and one of the said high resistance magnets controlling the circuit of the other high resistance magnet of the preceding section, the said last-named high resistance magnet also controlling the circuit of the said low resistance magnet and the said first-named high resistance magnet of the said preceding section, and means associated with the first-named high resistance magnet for establishing a circuit between the said contact section and the said first-named high resistance magnet independently of the said second-named high resistance magnet, whereby the current passing through either the high resistance magnet or the low resistance magnet will control the amount of current fed to each of the preceding sections.

42. In an electric car controlling system, the combination of a main feed conductor, a contact wire, a return conductor, a low resistance circuit and a high resistance circuit connected to the said main feed conductor and to the said contact wire, an electro-magnet for controlling the said circuits, and means associated with the high resistance circuit for preventing a change in the amount of current fed to the contact wire until the circuit is broken between the contact wire and the said return conductor.

43. In an electric car controlling system, the combination of a main feed wire, a contact wire, a return conductor, an electro-magnet for controlling the amount of current fed to the said wire and means associated with the said magnet for preventing any change in the amount of current fed to the said wire until the circuit between the said wire and the said return conductor has been broken.

44. In an electric car controlling system, the combination of a main feed wire, a contact wire, a return conductor, a high resistance magnet and a low resistance body connected to the said main feed wire, operative means located on said car and a high resistance connected in shunt to the said operative means, an electromagnet for connecting either the said high resistance magnet or the low resistance body to the said contact wire, whereby the current allowed to pass through the said contact wire will be sufficient to operate the said high resistance magnet.
- 10 45. In an electric car controlling system, the combination of a main feed wire, a contact wire, a return conductor, a high resistance electromagnet and a low resistance electro-magnet connected to the said main feed wire, means

for connecting either the said high resistance magnet or 15 the low resistance magnet to the said contact wire, an electric motor for operating the said car, a resistance connected in shunt with the said electric motor whereby sufficient current will be allowed to pass through the said high resistance electromagnet to cause the same to be 20 operated.

In testimony whereof, I have signed my name to this specification, in the presence of two subscribing witnesses.

CHARLES P. BREESE.
